GRAB

Filed Feb. 24, 1930

UNITED STATES PATENT OFFICE

STANLEY S. GALBRAITH, OF FARMINGTON, TENNESSEE

GRAB

Application filed February 24, 1930. Serial No. 430,903.

My present invention has reference to a grab for cleaning or recovering articles from well casings, etc., and my object is to provide a device which will grapple and automatically take hold of objects with which it comes in contact.

A still further object is the provision of a grab with claw-like jaws that are spring influenced to swing the same toward each other, 10 and that are held in open position by a trigger device of a novel construction.

A still further object is the provision of a grab that shall be of an extremely simple construction, wherein the parts constituting 15 the same may be readily disassociated should occasion require and one that may be set without liability of danger to the user, and one which will effect a powerful grip upon the article to be engaged thereby.

20 To the attainment of the foregoing and other objects which will present themselves as the nature of the invention is better understood, the improvement also resides in certain other novel features of construction, 25 combination and operative association of parts, one satisfactory embodiment of which is disclosed by the accompanying drawings.

In the drawings:

Figure 1 is a side elevation of the improvement with parts in section, the jaws of the grapple being in set position.

Figure 2 is a similar view with the jaws closed.

Figure 3 is a bottom plan view looking at 35 the device disclosed in Figure 1.

Figure 4 is a perspective view of the trigger.

Figure 5 is a similar view of one of the 40 jaws.

As disclosed by the drawings the improvement contemplates the employment of a tubular body in the nature of a pipe member 1. The pipe has its upper end closed by a threaded plug 2, and to the said upper or outer end of the plug there is pivotally secured the arms of a bail 3 to which the cable is attached.

The second end of the body 1 is flattened 50 from the opposite sides thereof to provide

parallel spaced extensions 4, the ends of the said extensions being open.

Secured by removable pivots 5 between the said straight ends 4 of the body 1 there are the shank portions 6 of the gripping jaws. 55 By reference to the drawings it will be noted that the jaws are substantially T-shaped in plan and the central elements of these jaws afford the shanks 6. The lateral elements of the jaws have their ends integrally formed 60 with claws 7 which are directed toward each other, and by reference to Figure 3 of the drawings, it will be noted that the claws of one of the jaws are disposed inwardly with respect to the claws of the second jaw so that 65 the claws ride between each other when the jaws are closed.

The shanks 6 of the jaws of the improvement have their outer ends arranged at an angle to their juncture with the lateral portions 8 of 70 the said jaws, and the shanks 6, opposite their pivots 5 have their edges notched to form the same with transverse grooves 9 and the outer walls of these grooves are preferably disposed at an angle. The shanks of the jaws 75 are at all times contacted by lower cup members 10 that provide for the reception of the lower or outer end of the comparatively heavy coil spring 11. The second end of the spring is also engaged by a cup member 12 80 and this cup member is held positioned on the body 1 through the medium of a pin 13 that passes transversely through the body.

In the body, adjacent to the outer end thereof there is fixed a guide 14 for the stem 15 85 on a trigger 16. The outer end of the trigger member 16 is widened and the said trigger member is approximately centrally formed with a lateral enlargement in the nature of a block 17. The block is of a size to be freely 90 received between the ends 4 of the body 1. The block has its lower portion formed with lateral extensions 18 and the outer end of the said block is formed with tongues 19 whose outer walls are at an angle and whose inner 95 walls are straight and divided from the outer flat portion 20 of the trigger by notches 21.

Arranged around the part 15 of the trigger and exerting a pressure between the stop 100

member 14 and the shoulder provided by the inner end of the block 17 there is a comparatively light helical spring 22.

As disclosed by Figure 1 of the drawings the outer and widened end of the trigger 16 projects beyond the pointed ends of the claws 7 of the jaws when the jaws are in open position, and when in such position the tongues 19 are received in the grooves 9 of the shanks 6 and the pressure exerted by the spring 22 holds the jaws thus open. The contact of the trigger member with an article in a well casting will move the trigger against the pressure of the comparatively light spring 22, permitting the expansion of the heavy spring 11 which swings the jaws to closed position to effectively grapple an obstacle therebetween. The device is set by a pressure against the cup 10 for compressing the spring 11 and thereafter by swinging the jaws to the position disclosed by Figure 1, when the said jaws are automatically engaged by the tongues on the trigger. The parts constituting the improvement are all removable, the spring 11 being released from the tubular body by the removal of the pin 13, the jaws being separated from the body by the removal of the pivots 5, in which instance the trigger will readily slide out of the body. Also if desired, the stop element 14 may be in the nature of a pin or like removable member which has a central opening that affords a guide passage for the part 15 of the trigger. It is believed the construction of the improvement and the advantages thereof will be understood and appreciated by those skilled in the art to which such invention relates so that further detailed description will not be apparent. Obviously I wish it understood that I do not desire to be restricted to the precise details herein set forth and, therefore, hold myself entitled to make such changes therefrom as fairly fall within the scope of what I claim.

Having described the invention, I claim:

- 45 1. A grapple of the class described, including a hollow body having one of its ends slotted longitudinally, gripping jaws having shank portions which are pivoted in the said slotted portion of the body and which shanks 50 opposite their bolts are notched, upper and lower cup members slidable on the body, a pin for holding the upper cup member on the body, a comparatively heavy coil spring 55 having its ends received in the cup members, a trigger having a block portion which is guided in the slotted portion of the body and having an extension which is guided in the body, a comparatively light spring urging 60 the trigger outward through the body, the block portion of the trigger having lateral extensions which are received in the slotted portions of the body and which have their outer faces formed with tongues to be received 65 in the grooves in the shanks of the

jaws, and the lower cup at all times contacting with the shanks of said jaws.

2. A grapple of the class described, including a hollow body having one of its ends slotted longitudinally, gripping jaws having shank portions which are pivoted in the said slotted portion of the body and which shanks opposite their bolts are notched, upper and lower cup members slidable on the body, a pin for holding the upper cup member on the body, a comparatively heavy coil spring having its ends received in the cup members, a trigger having a block portion which is guided in the slotted portion of the body and having an extension which is guided in the body, a comparatively light spring urging the trigger outward through the body, the block portion of the trigger having lateral extensions which are received in the slotted portions of the body and which have their outer faces formed with tongues to be received in the grooves in the shanks of the jaws, and the lower cup at all times contacting with the shanks of said jaws, said jaws comprising members which are of substantially T-shaped formation, the central elements affording the shanks, and claws integrally formed on the ends of the lateral elements of the jaws.

In testimony whereof I affix my signature.

STANLEY S. GALBRAITH.
